DESIGN FOR AN ELECTRIC CONNECTOR

Hugh B. Gould, Berwyn, Ill., assignor, by mesne assignments, to Francis C. Kollath, Chicago, Ill.

Application May 29, 1946, Serial No. 130,229

Term of patent 14 years

(Cl. D26--1)

To all whom it may concern:

Be it known that I, Hugh B. Gould, a citizen of the United States, residing at Berwyn, Cook County, Illinois, have invented a new, original, and ornamental Design for an Electric Connector, of which the following is a specification, reference being had to the accompanying drawings, forming a part thereof.

Fig. 1 is a perspective view of an electric connector, showing my new design;

Fig. 2 is an end view of the left end of Fig. 1;

Fig. 3 is an end view of the right end of Fig. 1; and

Fig. 4 is an elevational view.

I claim:

The ornamental design for an electric connector, as shown.

HUGH B. GOULD.
